UNITED STATES PATENT OFFICE.

HENRY E. WEBER, OF CANTON, OHIO, ASSIGNOR TO THE WEBER DENTAL MANUFACTURING COMPANY, OF CANTON, OHIO, A CORPORATION OF OHIO.

CUSPIDOR.

1,233,826.

Specification of Letters Patent. Patented July 17, 1917.

Application filed March 25, 1916. Serial No. 86,820.

To all whom it may concern:

Be it known that I, HENRY E. WEBER, a citizen of the United States, residing at Canton, in the county of Stark and State 5 of Ohio, have invented certain new and useful Improvements in Cuspidors, of which the following is a specification.

The invention relates to a cuspidor provided with the usual water supply, overflow 10 and waste pipes, and ordinarily mounted at the side of a dental or other chair; and especially to cuspidors in which the supply pipe is provided with a plurality of discharge nozzles for various purposes, as for 15 instance for flushing the bowl, for ejecting saliva and for filling a drinking cup.

In cuspidors of this type, the drinking cup is usually mounted on a bracket at one side of the cuspidor bowl, and is supplied 20 with water from an upright faucet having an arched outlet end discharging downward into the cup.

In the use of the drinking cup and its supply faucet, it frequently happens that 25 the cup will overflow when it is in place, and that there will be a leakage from the faucet when the cup is removed from its bracket. In either case, such an overflow or leakage fouls and corrodes the valves and 30 adjacent parts to such an extent as to render them not only unsightly but unsanitary, unless they are attentively cleaned by the operator; and it has been found in practice that although an operator may be very per- 35 sistent in cleaning the cuspidor bowl, a like attention to the valves and adjacent parts is usually neglected.

Furthermore, in the work of dental surgery, it is frequently necessary or desirable 40 for the operator to have a conveniently available basin for cleansing his fingers, his tools and other objects, and the purpose of the present invention is to add such a basin to the ordinary parts of a cuspidor of this 45 type; to utilize the basin as a shield for the valve parts and to receive the overflow and leakage from the drinking cup and its faucet; to locate the basin around the upright stem of the faucet; to provide a drainage outlet from the bottom of the basin 50 around the stem, with a valve for damming the water a certain depth in the basin; to swivel the upright faucet and provide a valve therein for opening in one or more 55 different positions; and to swivel a bracket

for the drinking cup around the stem of the upright faucet, so that the cup may be swung into different positions over the basin.

These objects of the invention, and ancillary advantages of construction, operation 60 and use, are attained by the embodiment thereof illustrated in the accompanying drawings, forming part hereof, in which—

Figure 1 is a side elevation showing the improved basin and adjacent parts applied 65 to the side of a cuspidor bowl;

Fig. 2, a vertical section of the same;

Fig. 3, a detached perspective view of the valve head;

Fig. 4, a detached perspective view of the 70 drinking cup faucet and affiliated parts;

Fig. 5, a detached perspective view of the clamping spider;

Fig. 6, a detached perspective view of the damming valve; and 75

Fig. 7, a detached perspective view of the cup bracket.

Similar numerals refer to similar parts throughout the drawings.

In the type of cuspidor employed for 80 illustrating the present invention, the cuspidor bowl 1 is mounted on a bracket (not shown) having a tubular branch 2 extending upward alongside the bowl and forming a waste or overflow channel therefrom; 85 on the outer side of which branch is provided the upright tubular bearing 3 in which the supply pipe 4 is adapted to be adjusted upward and downward and secured in place, by means of the set screw 5 operating in the 90 longitudinal groove 6 formed in the side of the supply pipe.

The valve head shown in Fig. 3 is formed on the upper end of the supply pipe and may include the cases 7, 8 and 9 of the 95 valves 7, 8 and 9, for the bowl flushing nozzle 10, drinking cup faucet 11, and saliva ejecting tube 12. The valve head is furthermore made hollow between the several valve cases to form the waste chamber 100 13, which discharges through the pendent waste tube 14 leading outwardly from one side of the chamber into the waste channel in the tubular branch 2 of the supporting bracket. 105

The annular rabbeted seat 15 is formed in the top of the valve head around an opening 16 which communicates with the waste chamber 13. This seat is preferably provided with the resilient gasket 17 thus 110

constituting a cushioned support upon which rests the pendent funnel flange or neck 18 formed around a central opening 19 in the bottom 20 of the basin 21.

- 5 The tubular post 22 is formed in the center of the valve head and extends upward through the opening 16 in its top, and the bowl is secured upon the annular seat 15 by means of the clamping collar 23 screwed 10 upon the post 22, and the intervening spider 24; which spider is preferably made of spring steel or other resilient material, in the form of a ring surrounding the post 22 and provided with the radial fingers 25 extending 15 outward over and upon the funnel neck 18 on the bottom of the basin, thus forming a free annular way around the post for the drainage of water through the funnel neck from the bottom of the basin 20 into the waste chamber of the supporting head.

The basin 21 may be made of glass, porcelain, or other brittle or fragile material, and it is evident that by the means described, the basin can be securely supported and clamped upon the metallic seat on the supporting head, without danger of cracking or breaking the funnel neck.

The upright tubular stem 26 of the drinking cup faucet 11 is provided with the valve 27 on its lower end, which valve is shaped as an inverted cone and is provided with a diametric port 28 communicating with the hollow 29 of the stem. The corresponding conical seat 30 is provided in the bottom of the tubular post 22 of the valve head, from the side of which seat extends the water inlet port 31, which in turn communicates with the valve chamber 32 into which leads 35 the supply port 33 communicating with the supply pipe 4, which inlet port is adapted to be opened and closed by means of the valve 8.

The conical valve 27 is rotatably secured 40 on its seat by means of the bearing sleeve 34, the spiral spring 35 and the washers 36 and 36^a, which surround the tubular stem of the faucet; the upper washer 36 bearing against the recessed annular shoulder 37 formed in 45 the lower end of the bearing sleeve 34, the lower washer 36^a bearing upon the annular seat 38 formed by the upper end of the conical valve, and the lower end of the bearing sleeve 34 being screwed as a stuffing box into 50 the upper end of the tubular post 22.

By this construction and arrangement it is evident that when the valve 8^a is open, water from the supply pipe 6 is free to flow through the faucet 11 when it is rotated to 55 register either one end or the other of the diametric port 28 with the inlet port 3; and that the conical valve 27 will be closed against the flow of water when the faucet is rotated upon its axis in all other positions.

60 The drainage aperture 39 is preferably

provided in the wall of the tubular post 22 near above the top of the conical valve, so as to permit any water which may leak upward around the valve to escape directly into the waste chamber 13 and thereby prevent the same from working upward around the tubular stem of the faucet.

The bell-shaped collar 40 is mounted upon the steep thread 41 around the bearing sleeve 24 and is preferably provided with the annular gasket 42 in its lower rim, so that by turning the collar downward its rim can be closed as a valve against the bottom of the basin, thus forming a dam which prevents a drainage of water from the basin directly 80 through the funnel neck into the waste chamber; and by turning the collar upward, such drainage is freely permitted.

The annular slots 43 are preferably provided in the upper portion of the drainage 85 valve, and it is evident that by turning this valve downward against the bottom of the basin, the same can be filled with water up to the openings of the slots, and that any excess of water will escape through the openings and downward through the waste chamber into the waste pipe. The use of this collar permits the basin to be used either as a catch basin for the drainage of water overflowing from the drinking cup or leaking 95 from the faucet, or as a wash basin for cleansing the fingers, tools or other articles, as may be desired, by merely turning the valve upward or downward as the case may be.

The upper end of the screw sleeve is 100 slightly tapered and forms a conical journal 44 for the correspondingly tapered opening 45 in the upright bearing 46 formed on the shank 47 extending from one side of the bracket 48 for the drinking cup 49; which 105 bracket is preferably located within the rim of the basin; and by this construction it is evident that the bracket may be rotated into any desired position around the faucet, and that because of the tapered form of its bearing, it will remain in any given position.

For the purpose of further protecting the valve head, the shield 50 having the depending rim 51 may be employed, and when used, this shield is provided with a central opening 52 surrounding the supporting seat on the top of the valve head, and the depending rim is provided with suitable notches 53 for receiving the valve parts.

I claim:

1. A basin having a funnel neck in its bottom, a faucet having an upright stem extending upward through the opening of the funnel, and a cup bracket mounted on the stem of the faucet.

2. A basin having a funnel neck in its bottom, a faucet having an upright stem extending upward through the opening of the funnel, and a cup bracket swiveled around the stem of the faucet.

130

3. A basin having a funnel neck in its bottom, a faucet having an upright stem extending upward through the opening of the funnel, a tapered bearing around the stem, and a cup bracket swiveled on the tapered bearing.
4. A basin having a funnel neck in its bottom, a faucet having a tubular stem extending upward through the opening of the funnel and a valve on its lower end with a port therein, a supply pipe communicating with the port and a seat upon which the valve may be rotated to open and close the port.
15. 5. A basin having a funnel neck in its bottom, a faucet having a tubular stem extending upward through the opening of the funnel, and a valve on its lower end with a plurality of ports therein, and a seat upon which the valve may be rotated to open and close the respective ports.
6. A hollow support having an opening in its top, a basin having a funnel neck secured on the rim of the opening, a faucet having a stem extending upward through the opening of the funnel, and a bell-shaped valve surrounding the stem, with means for adjusting the rim of the valve to and from the bottom of the basin.
30. 7. A hollow support having an opening in its top, a basin having a funnel neck secured on the rim of the opening, a faucet having a stem extending upward through the opening of the funnel, and a bell-shaped valve surrounding the stem having an opening in its side, with means for adjusting the rim of the valve to and from the bottom of the basin.
40. 8. A hollow support having an opening in its top, a basin having a funnel neck secured on the rim of the opening, a faucet having a stem extending upward through the opening of the funnel, a bearing sleeve around the stem, a bell-shaped valve screwed upon the bearing sleeve for adjusting the rim of the valve to and from the bottom of the basin.
45. 9. A hollow support having an opening in its top, a basin having a funnel neck secured on the rim of the opening, a tubular post on the support extending upward through the opening having a valve seat in its bottom, a faucet having a stem extending upward through the opening of the funnel with a valve on its end rotatable on the seat,
55. a bearing sleeve around the stem, and a spring bearing against the sleeve for pressing the valve upon its seat.
10. A hollow support having an opening in its top, a basin having a funnel neck secured on the rim of the opening, a tubular post on the support extending upward through the opening having a valve seat in its bottom, a faucet having a stem extending upward through the opening of the funnel with a valve on its end rotatable on the seat, there being an opening in the wall of the post near above the valve communicating with the hollow of the support.
11. A hollow support having an opening in its head with a rabbeted seat around the opening, a gasket in the seat, a basin with a funnel neck resting on the gasket, a post on the head extending upward through the funnel opening, a resilient spider comprising a ring around the post and radial fingers resting on the funnel neck, and a clamping collar screwed upon the post against the spider.
12. The combination of a cuspidor having a waste tube leading therefrom, an adjacent support having a waste chamber with a connection leading from one side thereof into the waste tube, and a basin on the support having a funnel neck draining into the waste chamber.
13. The combination of a cuspidor having an overflow tube leading from one side thereof, an adjacent support having a waste chamber draining into the overflow tube, and a basin on the support having a funnel neck draining into the waste chamber.
14. The combination of a cuspidor having a waste channel leading therefrom, an adjacent hollow support having a waste chamber draining into the waste channel, a basin on the support having a funnel neck draining into the waste chamber, and a faucet for the basin having a stem extending upward through the funnel neck.
15. The combination of a cuspidor, an adjacent support forming valve cases and having a waste chamber therein, a basin on the support having a funnel neck discharging into the waste chamber, a faucet for the basin having a stem extending upward through the funnel neck, said basin overhanging and shielding the valve cases.

HENRY E. WEBER.
